UNITED STATES PATENT OFFICE.

GEORGE W. BRUNTON, OF SPRINGFIELD, OHIO.

CORN-PLANTER.

SPECIFICATION forming part of Letters Patent No. 700,731, dated May 27, 1902.

Application filed September 24, 1900. Serial No. 30,890. (No model.)

To all whom it may concern:

Be it known that I, GEORGE W. BRUNTON, a citizen of the United States, residing at Springfield, in the county of Clark and State 5 of Ohio, have invented certain new and useful Improvements in Corn-Planters, of which the following is a specification, reference being had therein to the accompanying drawings.

10 This invention relates to certain new and useful improvements in planters particularly designed for planting corn.

The general object of my invention is to provide a rigid frame structure and draft-pole 15 or tongue to which is connected seed-dropping mechanism, which may be elevated and lowered independently of said frame structure and pole.

Another object of my invention is to provide spring supporting-bars for the seed-dropping portion of the machine, whereby the machine will more readily adapt itself to uneven 20 places in the soil, so that the shoes will run into the soil substantially the same depth in 25 all of such places.

Another object of my invention is to provide release mechanism which may be operated from the driver's seat for releasing a check-row wire or chain when at the end of a 30 row or at other times.

My invention also relates to details of construction and organization hereinafter appearing and particularly pointed out in the claims.

35 In the accompanying drawings, on which like reference characters indicate corresponding parts, Figure 1 represents a plan view of my improved corn-planter; Fig. 2, a side elevation of the same; Fig. 3, a detail sectional view on the line $x-x$ of Fig. 6; Fig. 4, a sectional view taken on the line $y-y$ of Fig. 1 and looking in the direction of the arrows; Fig. 5, a detail view of one of the grain-hoppers, together with the operating mechanism 40 therefor, a portion of which is in section to facilitate illustration; Fig. 6, a plan view of one of the hoppers with the cover removed; Fig. 7, a detail side elevation of the check-row dropper mechanism; Fig. 8, an end view 45 of the same; Fig. 9, a plan view of what is shown in Figs. 7 and 8; Fig. 10, a detail view,

with parts in section, illustrating a hand device for operating the dropper-shaft; Fig. 11, an edge view of what is shown in Fig. 10; Fig. 12, a detail view of a yielding bearing 55 for the main supporting or operating shaft; and Fig. 13, a detail view, with parts in section, of the clutch mechanism.

The letter A represents a pair of ground-wheels mounted on a main axle or shaft B, 60 which carries a frame structure C. Upon the frame structure is mounted a seat D, in the usual or any approved manner, at or near its rear end, while upon its forward end is carried a pole or tongue E, secured to the respective 65 cross-bars F and G of the frame structure. A pair of braces H are connected at one end to the cross-bar G and at their other end to the cross-bar F and act to brace the cross-bar F, so that it will more readily sustain the pulling 70 strain of the seed-dropping mechanism hereinafter referred to. Upon the frame structure C is also mounted a pair of brackets H', which are adapted to receive the ends of a rock-shaft I. This rock-shaft carries a pair of arms J and 75 K, which project from one side thereof, as also a foot-lever L, extending from the opposite side thereof, and a hand-lever M, the latter of which carries a detent O and is adapted to engage with a locking-segment P at one 80 side of one of the brackets H'. The arms J and K engage with spring-bars Q, which act to support the dropper mechanism, as will hereinafter appear. The forward ends of these spring-bars are fixedly connected with 85 the cross-bar F. By referring to Figs. 2 and 4 particularly it will be observed that to the under side of each of these spring-bars is attached a lifting-bar R, which extends beneath a valve-operating shaft S, carried by 90 the dropper mechanism, and is turned upward at its forward end and abuts against the bar X', in which position it is secured by means of a bolt a, passing through the bar, as also a bracket Z, hereinafter referred to. 95

Referring now particularly to the dropper mechanism, it will be seen that to the under side of the cross-bar F and near its outer ends is pivotally attached a curved shoe T. Each of these shoes curves downward and rearward and projects within a slot U (see Fig. 3) in the lower end of a boot V. This boot is 100

enlarged at its lower end to constitute a furrow-opener and at its upper end is connected with a seedbox W, the construction being in duplicate at each side of the machine. These 5 seedboxes are connected with each other by means of a dropper-shaft X, which extends through bearings Y, projecting downward from each box, and also by means of a rectangular bar X', to which the boots are bolted. 10 The spring-bars Q extend over the rectangular bar X' and are rigidly secured thereto by means of brackets Z, which are also rigidly secured to the spring-bars by bolts b. By this means the rectangular bar X' is supported, as also the seed boxes or receptacles 15 W. Upon the dropper-shaft beneath the seed-receptacles is mounted a bevel-gear 2, one for each receptacle. These bevel-gears engage with bevel-gears 3 on the under side 20 of dropper-disks 4' of any approved construction. The bevel-gears 2 are so arranged on the shaft as to drive both dropper-disks in the same direction, so that they will both discharge the grain from the grain-receptacles W at the same time through the 25 dropper-plates in a manner well known.

Referring again to the valve-operating shaft S, it will be seen that it is carried in projections 4, extending from the boots V. 30 This shaft is adapted to rock or partially rotate in its bearings. From Figs. 2 and 3 particularly it will be seen that this valve-operating shaft is square. This is for the purpose of more readily attaching to such bar 35 clips 5, which are fixedly clamped thereto by means of bolts 6. There is one of these clips near each end of the bar. To the outer end of each of these clips is connected one end of a link 7, while its other end is connected with 40 a valve 8, pivotally supported in the boot V.

I will now refer to the manner in which the valve-operating shaft is made to rock. From Fig. 10 particularly it will be seen that to such shaft is clamped an arm 9. This arm 45 extends beneath a disk 10, mounted on the dropper-shaft X. This disk carries lugs or projections 11, there being four in number, which are adapted to contact with the arm 9 to rock it downward. As soon as one of these 50 lugs has passed out of engagement with the arm said arm is again thrown into engagement with the disk 10 by means of a pair of springs 12, one end of each of which is secured to clamps 13, while the other end of each of these springs is secured to lugs 14, 55 extending from the rear of the respective boots. As the shaft S is rocked the valve 8 in each boot is opened and closed. This permits the grain to drop into the furrow 60 formed by the furrow-opener from the passage 15, which receives the grain through the dropper-plate, it being understood that the dropper-plate is so timed with respect to the valves that the grain is dropped into the passage 15 through the dropper-plate and rests upon the valve 8 until the valve 8 is rocked

by the rock-shaft in the manner above described. Projecting from one side of the disk 10 may be seen four pins 16, there being as many pins as there are lugs 11. These 70 pins are adapted to be engaged by a hand dropper device, hereinafter described, so that when such device is operated the dropper-shaft X is rotated in order that the grain may pass from the grain-receptacles into the boot 75 or delivery-spout.

Referring now to the mechanism for operating the dropper-shaft by the means of a check-row wire, it will be seen that on each side of the machine adjacent to the grain-receptacles is mounted an iron bracket 17, which is screwed or otherwise secured to an arm 18, projecting forward from the boot V near its upper end. This bracket has a wheel-support 19, pivotally connected therewith, as 80 shown at 20. (See Figs. 2 and 7 particularly.) This wheel-support carries a pair of rotatable wheels or pulleys 21, one at each end. A check-row wire, as indicated at 22 in dotted lines in Fig. 2, is adapted to pass over the 85 pulleys or wheels 21 when the wheels are in the position indicated in Fig. 7. A trip-catch 23, pivoted upon the bracket 17, as shown at 24, acts to engage with the wheel-support to hold it in an elevated position, as shown in 90 Figs. 7 to 9, inclusive. To this trip-catch is connected a rope 25, which extends to near the operator's seat within convenient reach of the operator. By pulling the rope the trip-catch is disengaged from the wheel-support 95 and such wheel-support is allowed to turn downward to the position indicated in dotted lines in Fig. 8. This will permit the check-row wire to be quickly disengaged from the machine, so that the dropper-shaft will not 100 be operated thereby. A spring 26 normally acts to return the trip-catch into the proper position for it to again engage with the wheel-support, when such support is again thrown upward by taking hold of it and raising it. 105 Any ordinary check-row wire may be employed. Such check-row wire when riding over the pulleys or wheels 21 also passes through the bifurcated lever 27, such lever being pivoted to the bracket at 28. To the 110 lower end of the lever is pivotally connected one end of a link 29, the other end of which is connected with another link 30, which carries a pawl 31, such latter link being also pivotally connected with an arm 32, pivoted 115 about the main dropper-shaft X. Let it be supposed that a knot 34 on the check-row wire 22 (indicated in dotted lines in Fig. 2) is engaging with the bifurcated lever and is throwing such lever rearward from its full-line position, as indicated in Figs. 2 and 7. This will cause the pawl 31 through the link 29 to act upon the teeth 11, extending from the disk 10, to partially rotate the dropper-shaft. As soon as this is accomplished and 120 the knot 34 slips past the bifurcated lever a spring 36, one end of which is secured to the 125

bracket 17 and the other end of which is secured to the lower end of the bifurcated lever, acts to return such lever to its full-line position, as indicated in Fig. 7. This also 5 turns the pawl 31 to its full-line position, so that as the bifurcated lever is again operated by another knot or ball on the check-row wire the pawl 31 again engages with another one of the teeth or projections 11 to further 10 rotate the disk 10 and dropper-shaft. In order that there may be some slight play on the lever when the check-row wire engages such lever, it will be observed that in the lever is formed a ball-and-socket joint, as shown at 15 Fig. 37. This permits a slight yielding of the lever before the dropper-shaft is actually operated, although the pawl 31 is brought snugly into contact with one of the teeth or projections, so that there is no sudden jerk, as it 20 were, acting upon the dropper-shaft the instant the check-row wire contacts with the bifurcated lever. In order that the check-row wire may not jump out of the pulleys or wheels when the machine is going over the 25 field, it will be observed that the bracket 17 has extensions 39 at its upper end, which extend over the wheels or pulleys, so that it is impossible for the check-row wire to become disengaged from the wheels or pulleys until 30 after the trip-catch is disconnected from the wheel-support, when the wheel-support will drop to its dotted-line position, as shown in Fig. 8, as above described.

Should it be desired to operate the machine 35 by hand, it will be seen that to the frame structure is secured a support 40, to which is pivoted a bell-crank hand operating-lever 41. To this operating-lever is pivoted a ratchet-arm 42, which is adapted to engage with one 40 of the pins 16 at a time. The ratchet-arm 42 also carries another ratchet-arm 43, which is pivoted thereto and which also is adapted to engage with one of the pins 16. As the hand-lever 41 is operated in one direction 45 the ratchet 42, acting on one of the pins 16, serves to partially rotate the disk 10, together with the dropper-shaft X. Upon moving the hand operating-shaft in the opposite direction the ratchet 43, acting on one of the pins 50 16, also serves to partially rotate the dropper-shaft in the same direction. Thus with my organization I am enabled to operate the dropper-shaft in one direction both by a forward and a backward movement of the bell-crank operating-lever.

I will now refer to the manner in which the dropper-shaft may be constantly rotated, whereby the machine may sow in drills instead of in hills. From Figs. 1 and 2 particularly it will be observed that upon the main shaft is mounted a pair of clutch members 44 and 45, respectively. The clutch member 45 is loose upon the shaft and is held in engagement with the clutch member 44 by means of 65 a spring 46, one end of which abuts against the clutch member 45 and the other end against a collar 47, keyed or otherwise se-

cured to the shaft. A pair of bearings 48, Fig. 13, extend beneath the main frame C, one on each side of the main axle B. In these 70 bearings is mounted a shaft 49, which carries a pair of cam-arms 50 51. These cam-arms are adapted to bear against a sprocket-wheel 52, secured to the clutch member 45, so as to move the sprocket-wheel sidewise, as also the clutch 75 member 45. This operation disengages the clutch member 45 from the clutch member 44. In order that the cam-arms may be operated, I provide a bar 54, which is bolted to a lateral extension of the cam-arm 51. This bar 80 extends beneath the foot-lever L, (see Figs. 1 and 2,) so that as the foot-lever is pressed downward a lug 55, projecting from the foot-lever, strikes the top of the bar 54 and acts to depress such bar, thereby operating the 85 shaft 49 and cam-arms 50 and 51. A sprocket-chain 56 passes over the ratchet-wheel 52 and also over a sprocket-wheel 57, mounted on the main dropper-shaft X. The sprocket-chain is employed where the dropper-shaft is 90 desired to rotate continuously, so that the machine will sow the seed in drills instead of planting it in hills, as is the case where it is operated by hand or by the check-row wire. When it is desired to sow the seed in hills, 95 the driving connection is interrupted either by disconnecting the clutch members or by removing the chain from the machine entirely.

In order that the sprocket-chain may not 100 receive severe shocks, such as it might receive when the dropper mechanism dropped into a depression or hole, it will be observed from Figs. 2 and 12 particularly that the main shaft is mounted in yielding bearings 105 58, which are held in place by means of springs 59. As the chain is drawn taut the spring 59 yields, so that the main axle B may move in the bearing toward the dropper mechanism. This will compensate for any movement of the dropper-shaft and will prevent the sprocket-chain from becoming too taut.

I will now describe the operation of my improved organization. The hoppers or grain-receptacles W are filled with grain and the 115 operator lowers the dropper mechanism by means of the hand-lever M, so that the shoes T come into contact with the ground and the furrow-openers form a furrow therein. If a check-row wire is used, such check-row wire 120 acts to operate the dropper-shaft, so that the dropper-disks in the hopper are rotated whenever the dropper-shaft is rotated. When this takes place, as much grain falls into the boot and upon the valve 8 as can pass through one 125 of the usual openings 60 in the disk when such opening comes over the upper end of the boot. At the same time the grain is held in the boot by the valve 8 until the valve-operating shaft S is partially rotated by means of the arm 9 130 coming in contact with the projections 11, extending from the disk 10 on the dropper-shaft X. The instant the arm 9 is operated the valve 8 is swung backward and down-

ward, so as to open the passage in the boot to the ground, thus permitting the grain to fall to the ground. The instant one of the projections 11 is out of contact with the arm 9 5 the valve 8 is again thrown across the passage in the boot by means of springs 12, one for each boot. Should the check-row wire be dispensed with, a person sitting upon the seat 61 (see Fig. 1) may take hold of the bell-crank 10 lever 41 and operate the pawls 42 and 43, which engage with pins 16, projecting from the disk 10, mounted on the dropper-shaft, so that the dropper-shaft may be rotated in the same direction for every backward and forward 15 movement of the bell-crank lever 41. In this manner the grain is dropped into the furrow in the same manner as just described.

In some instances it is desirable to sow the grain in drills instead of planting it in hills, 20 as is the case where the dropper-shaft is operated at regular intervals. This is accomplished by means of the sprocket-chain 56, which connects the sprocket-wheels 52 and 57 together, the latter being mounted on the 25 dropper-shaft X. The sprocket-chain is continuously operated by means of its connection with the main driving-axle, and consequently the dropper-shaft X is also constantly rotated, so that the grain is continuously falling 30 into the furrow. Where the machine is desired for planting in hills, the sprocket-chain 56 may be removed. It will also be observed that to the frame structure C is bolted or otherwise secured a chain-tightener 63, 35 which normally presses upon the chain to hold it taut. A spring 64 permits the lower end of the chain-tightener to yield, particularly when the dropper mechanism drops into a depression in the field.

40 Having thus fully described my invention, what I claim as new, and desire to secure by Letters Patent, is—

1. In a corn-planter, the combination, with a main frame structure provided with supporting and covering wheels, of a draft-pole rigidly secured to said frame structure, an auxiliary frame carrying furrow-opening and seed-dropping devices and pivotally connected 45 at its front end with the frame structure, a lever mounted on the frame structure, and connecting means between said lever and the auxiliary frame for raising and lowering said auxiliary frame, said connecting means comprising a spring, substantially as 50 described.

2. In a corn-planter, the combination with a pair of wheels, of a main shaft mounted therein, a frame structure carried by said main shaft, a tongue fixedly connected with 55 said frame structure, a frame carrying dropper mechanism and pivoted at its forward end to said frame structure, a spring connected with said frame structure at its forward end, a pivoted bar carried by said frame structure, a lever connected with said bar, a link connected with said spring and with said bar, whereby when said lever is raised and low-

ered said spring is also raised and lowered, and means for fixedly connecting said dropper-mechanism frame with said spring, all 7c substantially as shown and described.

3. In a corn-planter, the combination with supporting-wheels, of an axle rotated by said supporting-wheels, a frame structure mounted on said axle having a pole fixedly connected 75 therewith, a frame carrying dropper mechanism and pivoted at its forward end to said frame structure, a pair of spring-bars, one end of each of which is also secured to said frame structure, means for fixedly connecting said spring-bars with said dropper-mechanism frame, and adjustable means for connecting the inner ends of said spring-bars with said frame structure, whereby said dropper mechanism may also be adjusted, all 80 substantially as shown and described.

4. In a corn-planter, the combination with a pair of supporting and driving wheels, of a main shaft mounted in said wheels and operated thereby, a frame structure supported by 90 said shaft, a pivoted cross-bar also supported by said shaft having a pair of arms extending forward therefrom, and a foot-lever extending backward therefrom, a frame carrying dropper mechanism and pivoted at its forward end to said frame structure, a pair of springs connected with said frame structure at their forward ends, means for rigidly connecting said dropper-mechanism frame with 95 said springs, a pair of links connected with the respective spring-bars and also with the respective arms, and a hand-lever also connected with said cross-bar, whereby said spring-bars may be raised and lowered by hand, as also by foot-power, all substantially 100 as shown and described.

5. In a corn-planter, the combination with a frame structure, of a pair of spring-bars connected thereto at their forward ends, a frame carrying dropper mechanism and pivoted to 110 said frame structure at its forward end, means for rigidly connecting said dropper-mechanism frame with said spring-bars, a dropper-shaft and a valve-operating shaft carried by 115 said dropper mechanism, means for operating said dropper-shaft, means carried by said dropper-shaft for operating said valve-operating shaft, and a hand-lever connected with 120 said spring-bars for elevating and lowering said dropper-mechanism frame, all substantially as shown and described.

6. In a corn-planter, the combination, with a main frame structure, provided with a rotating axle having supporting and covering wheels, and a draft-pole rigidly secured to 125 said frame structure, of an auxiliary frame provided with furrow-opening and seed-dropping devices and pivotally connected at its front end to the main frame structure, means mounted on the main frame structure for 130 raising and lowering said auxiliary frame, check-row and hand operating devices carried by the auxiliary frame for actuating the seed-dropping mechanism, connecting mech-

anism between the main axle and the seed-dropping mechanism whereby the latter may be operated from the former, and means for throwing said connecting mechanism into and out of operation, substantially as described.

5 7. In a corn-planter, the combination with a dropper-shaft, of a lever, means for connecting said lever with said dropper-shaft to operate said shaft in one direction, said lever having a ball-and-socket joint therein and a bifurcated end, a pair of rollers, a check-row wire adapted to pass over said rollers and through the bifurcated end of said lever, and means for swinging said rollers and said bifurcated lever out of contact with said check-row wire, all substantially as shown and described.

10 8. In a corn-planter, the combination with a dropper mechanism, a dropper-shaft rotatably mounted therein, a lever pivotally supported thereby, said lever having its upper end bifurcated, a ball-and-socket joint in said bifurcated lever, whereby said bifurcated end may rotate, a pivoted frame structure, a pair of rollers carried thereby, a check-row wire adapted to pass over said rollers and through the bifurcated end of said lever, and means for holding said roller-frame in wire-supporting position and for releasing said roller-frame, whereby said rollers will swing out of wire-supporting position, at the same time the bifurcated end of said lever rotating to also release said check-row wire, all substantially as shown and described.

15 9. In a corn-planter, the combination with a dropper mechanism, of a check-row device mounted at each end of said dropper mechanism, a pivoted bifurcated lever carried by said check-row device having a ball-and-socket joint therein, a roller-frame pivoted to said check-row device, a pair of rollers carried thereby, a check-row wire adapted to extend over said rollers and be supported thereby and extend through the bifurcated end of said lever, a trip device for holding said roller-frame in position for said wheels to support said wire and for releasing said roller-frame, whereby said rollers, as also said bifurcated lever, disengage from said check-row wire, said lever being operated in one direction by said check-row wire, and a spring for operating said lever in the opposite direction, all substantially as shown and described.

20 10. In a corn-planter, the combination, with

a main frame structure provided with longitudinally-slotted bearings, of supporting and covering wheels provided with a rotating axle mounted in said bearings, an auxiliary frame carrying furrow-opening and seed-dropping devices and pivoted at its front end to the main frame structure, and operating mechanism connecting said seed-dropping devices and the axle, the said axle being mounted to yield longitudinally in its bearings, and springs for returning said axle to its normal position, substantially as described.

25 11. In a corn-planter, the combination with a pair of carrying-wheels having a main axle mounted therein and adapted to rotate therewith, of a frame structure having yieldable bearings within which said main axle is mounted, dropper mechanism pivoted to said frame structure, a dropper-shaft carried by said dropper mechanism, a sprocket-wheel mounted thereon, a sprocket-wheel mounted on said main axle, a sprocket-chain for connecting said sprocket-wheels with each other, said bearings yielding to permit said dropper mechanism to also yield without unduly stretching said sprocket-chain, all substantially as shown and described.

30 12. In a corn-planter, the combination with a pair of carrying-wheels having a main axle mounted therein, a frame structure mounted on said axle, a pivoted shaft carried by said frame structure, a pair of arms projecting from said shaft in a forward direction, and a foot-lever projecting from said shaft in a rearward direction, a hand-lever secured to said pivoted shaft, a toothed segment, a pawl carried by said hand device engaging with said toothed segment for holding said hand device in any desired position, whereby said pivoted bar is held in any desired position, dropper mechanism, a pair of spring-bars secured to said frame structure at one end and connected with said arms at their other ends, and means for rigidly connecting said dropper-shaft with said spring-bars, whereby when said foot-lever and said hand-lever are operated said dropper mechanism is elevated or lowered, all substantially as shown and described.

35 In testimony whereof I affix my signature in presence of two witnesses.

GEORGE W. BRUNTON.
